UNITED STATES PATENT OFFICE

CHARLES J. EVERETT AND JOHN V. McADAM, OF NEW YORK, N. Y.

MACHINE FOR WASHING AND DRYING PHOTOGRAPHIC SHEETS.

1,077,464.

Specification of Letters Patent.

Patented Nov. 4, 1913.

Application filed October 10, 1912. Serial No. 725,051.

To all whom it may concern:

Be it known that we, CHARLES J. EVERETT and JOHN V. McADAM, citizens of the United States, and residents of the borough 5 of Manhattan, in the city and State of New York, have invented a new and useful Improvement in Machines for Washing and Drying Photographic Sheets, of which the following is a specification.

10 The object of this invention is to provide a machine in which photographic sheets may be thoroughly and rapidly washed and dried without danger of wrinkling, creasing or tearing the sheets, and in which the manual 15 handling of the sheets is reduced to a minimum.

A practical embodiment of our invention is represented in the accompanying drawings, in which—

20 Figure 1 represents the machine in side elevation, Fig. 2 is a top plan view of the machine with its intermediate portions broken away, Fig. 3 is a vertical longitudinal section through the machine, Fig. 4 is a detail 25 transverse section showing more clearly the means for bringing the wringer into and out of operation, and Fig. 5 is a detail view of one of the belt spreader bars, the intermediate portion of the same being broken away.

0 The side frames of the machine are denoted by 1 and 2, between which side frames 4 a tank 3 for containing the liquid bath 4 for the sheets, is suitably supported. At the front of the machine above and into close 85 proximity to the liquid bath 4 a wringer is provided, which wringer is herein shown as comprising a pair of coating rolls 5 and 6, the roll 5 having an unyielding non-absorbent surface and the roll 6 a yielding porous, 40 preferably absorbent surface. Liquid is applied to the surface of the roll 5 from a liquid bath 7 carried in a basin 8, into which bath the bottom of the roll 5 projects.

The particular form of wringer herein 45 shown and described forms the subject matter of a copending application filed by us under even date herewith, its serial number being 725,050, filed October 10, 1912.

Between the liquid bath 4 and the wringer 50 is preferably disposed a water pipe 9 arranged to direct jets of water against the face of the sheet after it leaves the liquid bath 4 and before it reaches the wringer, for the purpose of washing the face of the sheet. 55 A cross bar 10 is also disposed between the

wringer and the liquid bath in position for guiding the sheet to the wringer.

Means 11 are provided for stripping the sheets from the roll 5 of the wringer after the sheets have passed between the rolls 5 and 6. The guides 12 are provided for guiding the sheet from the wringer onto an endless sheet carrier which is herein shown as a plurality of tapes 13 passing around end rollers 14, 15, and an intermediate tightener 60 roller 16.

17 designates a rotary drum which may be heated by any well known means such, for instance, as from a gas burner 18 extending into the interior of the drum. This drum 70 is mounted between the side frames 1 and 2, near the top of the machine at the rear thereof. An endless sheet carrier which comprises a wide belt 19 serves to pass the sheet being treated around the periphery of the 75 heated drum 17, which belt passes around rollers 20, 21, 22, 23 and 24. The roller 21 may be adjusted angularly by suitable devices 25 for preventing the lateral creeping of the belt 19 along the drum 17. Means are 80 also provided for keeping the belt 19 spread to prevent any wrinkling thereof, which means are herein shown as a plurality of bowed spreader bars 26, 27 and 28. Certain of these bars may be adjusted rotatively, 85 as, for instance, the bars 26 and 28, by nuts 29, 30, while the other bar 27 may be free to adjust itself automatically on the belt 19.

Fixed guides 31 are arranged in position to guide the sheets from the tapes 13 onto 90 the belt 19.

An endless sheet delivery carrier is arranged to receive the sheets after they leave the heated drum 17, which carrier is herein shown as a plurality of tapes 32 passing 95 around end rollers 33, 34. Means may be provided for heating this sheet delivery carrier, as, for instance, by providing a gas burner 35 arranged across the machine beneath the said carrier.

Means 36 are provided for stripping the sheets from the heated drum 17 and guides 37 are provided for guiding the sheets onto the tapes 32 of the sheet delivery carrier.

To keep the proper tension upon the sheet being treated, as it passes through the machine, it is desirable that the endless tapes 13 be driven at a slightly greater surface speed than the rolls 5 and 6 of the wringer, the endless belt 19 be driven at a slightly 110

greater surface speed than the endless tapes 13 and that the delivery carrier tapes 32 be driven at a slightly greater surface speed than the endless belt 19.

5 The driving mechanism shown for the several parts, is as follows: A cross shaft 38 is driven from a suitable drive shaft 39 at variable speeds through a friction driving connection 40, 41, the shaft 39 being driven 10 from any suitable source of power, not shown herein. A sprocket chain 42 passes around a sprocket 43 on the shaft 44 and a sprocket 45 on the shaft 38. A sprocket chain 46 passes around a sprocket wheel 47 15 on the shaft 44, a sprocket wheel 48 loosely mounted on the shaft 49 of the roll 5, a sprocket 50 on the shaft 51 of the roller 14, a sprocket 52 on the shaft 53, and a sprocket 54 on the shaft 55 of the roller 24. A driving belt 56 passes around a pulley 57 on the shaft 55 and around a pulley 58 on the shaft 59 of the roller 33. The relative sizes of 20 the various sprockets and pulleys are such as to secure the constantly increasing speed 25 of the different sheet carriers as the sheet passes through the machine.

Manually controlled means are provided for bringing the wringer into and out of operation, which means are herein shown as 30 comprising a clutch member 60 slidably keyed to the shaft 49 and arranged to be brought into and out of a clutch member 61 on the sprocket 48 by a rocking lever 62 connected to a foot treadle 63 by a flexible connection 64. A spring 65 tends to hold the clutch members in interlocking engagement.

In operation, the advance edge of the sheet being treated is manually lifted from 40 its liquid bath 4 and its advance edge inserted between the rolls 5 and 6 of the wringer. The wringer is then brought into operation and as the sheet is passed through the wringer its face will be washed by the 45 jets of water or other liquid issuing from the pipe 9. The strippers 11 will strip the sheet from the roll 5 and the guides 12 will direct the sheet onto the tapes 13 of the sheet feeding carrier. As the sheet reaches 50 the upper rear end of the carrier the guides 31 will direct the sheet onto the belt 19 and the sheet will be passed around the heated drum 17 between said belt and drum. The devices 36 will strip the sheet from the drum 55 17 and the guides 37 will direct the sheet onto the tapes 32 of the endless sheet delivery carrier. If found desirable, the sheet may be subjected to further heating while on the delivery carrier by using the burner 60 35. From the delivery carrier the sheet may be deposited into any suitable receptacle not shown herein.

Any tendency on the part of the belt 19 to become wrinkled is absolutely obviated by 65 the use of the bowed spreaders 26, 27 and 28,

it being understood that one or more of these spreaders may be used as found desirable. Furthermore, the constantly increasing speed of the different sheet carriers serves, at the same time, to keep a strain 70 upon the sheet being treated thus insuring the passage of the sheet through the machine without danger of becoming creased or wrinkled or torn.

What we claim is:—

1. In a machine for washing and drying photographic sheets, a heated drum around which the sheet is passed, and an independent heated sheet delivery device arranged to receive the sheet from the drum. 75

2. In a machine for washing and drying photographic sheets, a liquid bath, a wringer for receiving the sheet therefrom, a heated drum and an independent means for passing the sheet from the wringer to the drum 80 and means for passing the sheet around the drum. 85

3. In a machine for washing and drying photographic sheets, a wringer, a heated drum, independent means for passing the 90 sheet from the wringer to the drum and means for passing the sheet around the drum and an independent sheet delivery device arranged to receive the sheet from the drum. 95

4. In a machine for washing and drying photographic sheets, a wringer, a heated drum, independent means for passing the sheet from the wringer to the drum and means for passing the sheet around the drum and an independent heated sheet delivery 100 device arranged to receive the sheet from the drum. 105

5. In a machine for washing and drying photographic sheets, a liquid bath, a wringer arranged to receive the sheet therefrom, an 105 independent heated drum, independent means for passing the sheet from the wringer to and around the drum and a sheet delivery device arranged to receive the sheet from the drum. 110

6. In a machine for washing and drying photographic sheets, a liquid bath, a wringer arranged to receive the sheet therefrom, a heated drum, independent means for passing the sheet from the wringer to the drum, 115 means for passing the sheet around the drum and an independent heated sheet delivery device arranged to receive the sheet from the drum. 115

7. In a machine for washing and drying photographic sheets, a wringer, a heated drum, an endless belt carrier arranged to pass the sheet around the drum and an endless sheet carrier arranged to pass the sheet from the wringer to the endless belt carrier. 120

8. In a machine for washing and drying photographic sheets, a wringer, a heated drum, a belt carrier arranged to pass the sheet around the drum, an endless sheet car- 125 130

rier arranged to pass the sheet from the wringer to the belt carrier and an endless delivery carrier arranged to receive the sheet from the drum.

5 9. In a machine for washing and drying photographic sheets, a heated drum, a carrier arranged to pass the sheet around the drum, a delivery carrier arranged to receive the sheet from the drum and means for driving the delivery carrier at a greater surface speed than the first-named carrier.

10 10. In a machine for washing and drying photographic sheets, a carrier arranged to pass the sheet around the drum, a wringer, a carrier for passing the sheet from the wringer to the drum and means for driving the first-named carrier at a greater surface speed than the last-named carrier.

15 11. In a machine for washing and drying photographic sheets, a heated drum, a carrier arranged to pass the sheet around the drum, a wringer, a carrier for passing the sheet from the wringer to the drum and means for driving the last-named carrier at a greater surface speed than the wringer.

20 12. In a machine for washing and drying photographic sheets, a heated drum, a carrier arranged to pass the sheet around the drum, a wringer, a carrier for passing the sheet from the wringer to the drum, and means for driving the first-named carrier at a greater surface speed than the last-named carrier at a greater surface speed than the wringer.

25 13. In a machine for washing and drying photographic sheets, a heated drum, a carrier arranged to pass the sheet around the drum, a wringer, an independent carrier for passing the sheet from the wringer to the drum and an independent delivery carrier arranged to receive the sheet from the drum.

30 14. In a machine for washing and drying photographic sheets, a heated drum, a carrier arranged to pass the sheet around the drum, a sheet delivery carrier arranged to receive the sheet from the drum and means for driving the delivery carrier at a greater surface speed than the first-named carrier.

15. In a machine for washing and drying photographic sheets, a heated drum, a carrier arranged to pass the sheet around the drum, a wringer, a carrier for passing the sheet from the wringer to the drum, a delivery carrier arranged to receive the sheet from the drum and means for driving the delivery carrier at a greater surface speed than the first-named carrier and the first-named carrier at a greater surface speed than the second-named carrier.

16. In a machine for washing and drying photographic sheets, a heated drum, a carrier arranged to pass the sheet around the drum, a wringer, a carrier for passing the sheet from the wringer to the drum, a delivery carrier arranged to receive the sheet from the drum and means for driving the delivery carrier at a greater surface speed than the first-named carrier, the first-named carrier at a greater surface speed than the second-named carrier, and the second-named carrier at a greater surface speed than the wringer.

17. In a machine for washing and drying photographic sheets, a drum, an endless belt for passing a sheet around the drum and means for spreading the belt to prevent it from wrinkling.

18. In a machine for washing and drying photographic sheets, a drum, an endless belt for passing the sheet around the drum and a spreader bar for spreading the belt laterally to prevent it from wrinkling.

19. In a machine for washing and drying photographic sheets, a drum, an endless belt for passing the sheet around the drum and a bowed spreader bar for spreading the belt laterally to prevent it from wrinkling.

In testimony, that we claim the foregoing as our invention, we have signed our names in presence of two witnesses, this twenty- seventh day of September 1912.

CHARLES J. EVERETT.
